UNITED STATES PATENT OFFICE.

CARL W. WEISS, OF BROOKLYN, NEW YORK.

INTERNAL-COMBUSTION ENGINE.

1,263,173.

Specification of Letters Patent. Patented Apr. 16, 1918.

Application filed November 1, 1917. Serial No. 192,724.

To all whom it may concern:

Be it known that I, CARL W. WEISS, a citizen of the United States, and residing in the borough of Brooklyn of the city of New York, in the State of New York, have invented certain new and useful Improvements in Internal-Combustion Engines, of which the following is a specification, reference being had to the accompanying drawing, forming a part hereof.

This invention relates to internal combustion engines of that class in which the fuel oil, when the engine is running, is fed continuously and in which, therefore, the delivery of oil to the cylinder or cylinders may be continued when the engine is stopped unless provision is made to prevent the continued flow of the fuel oil. The object of the invention is to provide automatic means which shall operate when the engine stops to prevent the further flow of oil and shall operate when the engine is started and is running to permit the proper flow of oil. The invention will be more fully explained hereinafter with reference to the accompanying drawing in which it is illustrated and in which,—

Figure 1 is a view in elevation of an internal combustion engine which is equipped with the invention.

Fig. 2 is a detail view in section of one form of the device for preventing the flow of oil when the engine is stopped.

Fig. 3 is a view of the same, partly in elevation and partly in section, on the plane indicated by the broken line 3—3 of Fig. 2, looking in the direction of the arrows.

Fig. 4 is a view in elevation illustrating a slightly different embodiment of the invention.

In the engine shown in Fig. 1, which may be taken as an illustration of a type of engine to which the invention may be applied, the fuel oil is supplied under constant pressure from a tank *a*, through a suitable conductor *b*', to the fuel inlets *c*, through which it is admitted to the cylinders *d*, represented as arranged in pairs above the crank casing *e*. The engine is shown as provided with the usual crank-shaft *f* and fly-wheel *f*'.

At some convenient point in the oil conductor *b*, *b*' is interposed a cut-off valve *g*. As shown in Figs. 2 and 3, the valve casing *g*', which forms the continuation of and

the conductor, has a conical valve-seat to receive a valve-block *g*" which has two diametrical passages *g*³, *g*⁴ which intersect at an angle. When the valve-block *g*" is in the position shown in Fig. 3 the flow of oil therethrough is prevented, but when the valve-block receives a partial rotation, either in one direction or the other, one or the other of the passages *g*³, *g*⁴ is aligned with the conductor and permits the flow of oil.

In the construction shown in Figs. 1, 2, and 3 the stem or operating arm *g*⁵ of the valve-block carries a pin *g*⁶, which enters a slot *h*' in an arm *h* of a friction strap *h*² which embraces lightly a friction disk *f*² keyed on the shaft *f*. The strap *h*² is preferably formed in two parts which are held lightly together by pins *h*³ with interposed spring *h*⁴ so that the friction strap shall be turned with the shaft when the latter begins to rotate but shall not offer substantial resistance during the continued rotation. A spring *h* is connected at one end to a fixed point *h*', in line with the axis of the shaft *f* and the axis of the valve-block *g*", and at the other end to a pin *h*² fixed in the end of the arm *h*, so that the tendency of the spring is to hold the arm *h* in central position and therefore to hold the valve-block *g*" in closed position. The friction of the strap *h*² on the disk *f*², when the shaft *f* is rotating, is sufficient to overcome the tension of the spring *h*, so that as soon as the rotation of the shaft commences the valve is opened and thereafter is held open. On the other hand, as soon as the engine stops and the rotation of the shaft ceases the spring immediately pulls the arms *h* into central position and turns the valve-block *g*" so that it cuts off the flow of oil. It will be observed that in this construction the turning of the shaft *f* in either direction will open the valve and permit the flow of oil.

It may be desired, in some instances, to provide means whereby the starting of the engine in one direction only shall be permitted, the starting of the engine in the opposite direction being prevented. An embodiment of the invention adapted for this purpose is shown in Fig. 4. In this construction the valve-block *g*" has a single passageway *g*⁸ which is normally out of line of the oil conduit, as shown in Fig. 4, but may be turned into line therewith to permit the flow of oil. The operating arm *g*⁵, as before, has a pin *g*¹⁰ which enters a slot *h*³ in

an arm h^4 . The latter has connected, as at h^5 and h^6 , a flexible friction band h^7 , which embraces a friction disk f^3 on the shaft f . A compression spring k^3 , connected to the arm h^4 , tends to hold the arm h^4 in its central position against a stop h^8 and to hold the valve in its closed position.

The rotation of the friction disk f^3 in a clockwise direction acts with sufficient friction on the strap h^7 to move the arm h^4 against the spring k^3 and to hold it in position with the valve open, but not with sufficient friction to offer substantial resistance. Movement of rotation of the disk f^3 , 15 in the opposite direction, however, immediately acts, in a well known manner, through the band h^7 , to move the arm h^4 in the opposite direction so as to close the valve. The movement of the arm h^4 in this direction continues until it strikes the arm h^8 and the blocking of the further movement thereby then causes the friction band h^7 to act as a powerful brake upon the shaft f^3 , thereby locking it against rotation in a counter-clockwise direction as well as shutting off 25 the flow of oil.

Various other embodiments of the invention will readily suggest themselves in view of the foregoing and the invention therefore is not limited to the particular construction shown and described except as pointed out in the accompanying claims.

I claim as my invention:

1. In an internal combustion engine, the combination with means to supply fuel oil under pressure, of a shut-off valve to prevent or permit the flow of oil, means to close the valve, and devices actuated by the rotation of the engine shaft to open and hold 35 open the valve.

2. In an internal combustion engine, the

combination with means to supply fuel oil under pressure, of a shut-off valve interposed in the oil conduit, a spring acting normally to hold the valve closed, and devices actuated by the rotation of the engine shaft to open and hold open the valve.

3. In an internal combustion engine, the combination with means to supply fuel oil under pressure, of a shut-off valve interposed 50 in the oil conduit, means tending normally to close the valve, a friction disk mounted on the engine shaft, a friction band embracing the disk, and means actuated by the friction between the band and the disk as the shaft 55 rotates to open the valve.

4. In an internal combustion engine, the combination with means to supply fuel oil under pressure, of a shut-off valve interposed in the oil conduit, a spring connected with 60 the valve and tending to close the same, an operating arm secured to the valve, a friction disk mounted on the engine shaft, a friction band embracing said disk, and a slotted arm 65 engaging the friction band and in operative engagement with the operating arm of the valve.

5. In an internal combustion engine, the combination with means to supply fuel oil under pressure, of a shut-off valve to prevent 70 or permit the flow of oil, a brake member on the engine shaft, and a second brake member co-operating with the first brake member and operatively connected to the valve to close the valve and exert a braking action 75 on the shaft when the shaft rotates in one direction, and to open the valve and hold it open when the shaft rotates in the opposite direction.

This specification signed this 30th day of Oct., A. D. 1917.

CARL W. WEISS.
